UNITED STATES PATENT OFFICE.

CHARLES E. TOMLINSON, OF SYRACUSE, NEW YORK, ASSIGNOR, BY MESNE ASSIGNMENTS, TO INTERNATIONAL TIME RECORDING COMPANY OF NEW YORK, OF ENDICOTT, NEW YORK, A CORPORATION OF NEW YORK.

TIME-RECORDER.

1,103,105.

Specification of Letters Patent.

Patented July 14, 1914.

Application filed August 27, 1908. Serial No. 450,469.

To all whom it may concern:

Be it known that I, CHARLES E. TOMLINSON, of Syracuse, in the county of Onondaga and State of New York, have invented a certain new and useful Time-Recorder, of which the following is a specification.

My invention has for its object the production of a simple and efficient means for determining the successive positions of a shiftable element or part, which means is particularly adapted for that type of time recorders having its record-sheet support shiftable in two directions; and the invention consists in the combinations and constructions hereinafter set forth and claimed.

In describing this invention, reference is had to the accompanying drawing in which like characters designate corresponding parts in all the views.

Figure 1 is a side elevation, partly broken away and partly in section, of a portion of a time-recorder provided with one form of my invention. Figs. 2, 3 and 4 are enlarged detail views of parts shown in Fig. 1, illustrating the various steps in each operation of my invention. Figs. 5 and 6 are opposite elevations, partly broken away, of parts shown in section of Fig. 1. Fig. 7 is a detail view of parts seen in Figs. 2, 3 and 4, showing one of said parts as provided with means for changing its starting position. Figs. 8 and 9 are modified forms of the abutment detailed in Figs. 2, 3 and 4. Fig. 10 is a fragmentary view, partly in section, of another arrangement of parts seen in Fig. 1. Fig. 11 is a fragmentary view of a modified form of parts seen in Fig. 1, illustrating a double shiftable element shiftable laterally in opposite directions. Fig. 12 is a fragmentary view illustrating mechanism similar to that shown in Fig. 2, but operating in a different manner.

This invention comprises, generally, a shiftable element, and means for determining successive positions of said element, said means comprising two members, one of said members being shiftable with said element into and out of engagement with the other member, and one of said members being movable a predetermined distance by the other member, during each coöperation of said members, in a direction at an angle to the shifting movement of said element, in

order to relatively position said members for the next coöperation thereof.

I have here illustrated my invention as embodied in a workman's time-recorder of that type in which the record-sheet is wrapped around a drum rotatable for moving its rim or peripheral wall longitudinally and thereby bringing to the printing line, the different spaces assigned to the individual workmen, and shiftable axially or laterally for bringing different portions of said spaces to the printing point in order that successive records of each workman may be arranged side by side.

1 is the shiftable element or drum, here shown as mounted on a hollow shaft 2 journaled in the main frame 3 of the time-recorder, and provided with a hub 4 around the shaft 2. As here illustrated the drum 1 is rotated by means of a hand-operated shaft 5 extending through the hollow shaft 2 and connected to the hub 4 of the drum, by a key or pin 6, extending through a longitudinal slot 7 in the hollow shaft 2, the ends of said shaft 5 extending beyond opposite ends of the hollow shaft 2. In Fig. 1 the drum is shown as in its starting position, the position of the printing mechanism being indicated by the arrow 8, and the successive lateral positions of the printing point on the drum 1 being indicated by the arrows 9. The drum 1 is shiftable axially in the direction indicated by the arrows 10, Figs. 1, 2 and 3 in order to bring the printing mechanism (indicated by the arrow 8) opposite to successive points on the record-sheet, (indicated by the arrows 9) by an axial movement of the hand-shaft 5 within the hollow shaft 2.

The members for determining the successive positions of the element or drum 1 when shifted axially and when in any one of its positions assumed when moved about its axis are any one of a plurality of movable abutments 11 shown in Figs. 1, 2, 3 and 4 as fixed from shifting movement with the drum 1, and a controlling part 12 which is shown in said figures, as shiftable with the drum, there being the same number of abutments 11 as there are positions the peripheral wall or record-sheet carrying element 13 of the drum 1 may assume when shifted longitudinally by the rotation of the drum. For example, if the drum supports a record-sheet

divided into fifty spaces to receive the time registrations of fifty men, the drum may be moved about its axis into fifty positions and there will be fifty abutments 11. Said abutments 11 are illustrated in Figs. 1 to 6 inclusive as carried by frame elements as plates 14, 15, spaced apart in a direction lengthwise of the axis of the drum 1 and supported by the main frame 3, and as movable in a direction crosswise of the lateral movement of the drum 1, that is to say, toward and from the axis of the drum 1. As here illustrated the abutments 11 are movable in grooves or guides 16 formed in opposing faces of the plates 14, 15 and arranged radially with said axis, and are held in their various positions assumed in the guides by suitable devices here shown as springs 17 extending through radial slots 18 in the rear plate 14, and frictionally engaging the outer or rear face of said plate.

As best seen in Figs. 2, 3 and 4 each abutment 11 is formed with a series of steps or shoulders 19 corresponding in number to the number of lateral positions which the drum 1 is capable of assuming, each step or shoulder having engaging surfaces 20, 21 arranged at an angle to each other.

In the embodiment of my invention shown in Figs. 1 to 4 inclusive, the controlling member of part 12 is pivotally connected to the inner end of the shaft 5, so that its end is movable toward and from the shaft 5 in an arc 22 extending lengthwise of the shaft, and at the end of each axial movement of the shaft 5, the end of said member or part 12 engages the surface 20, of one of the shoulders of the abutment 11 opposite thereto, and is swung on its pivot, so that its end moves in the arc 22 away from the shaft 5, as shown in Figs. 2, 3 and 4, engages the surface 21 and moves the abutment 11 outwardly in the guide 16, the pivotal movement of said part 12 being against the action of a spring 120, so that when pressure on the end of the shaft 5 is released and the shaft returned axially to its starting position the part 12 will return to its starting position, Fig. 4, and its engaging end will be in the lowest point of the arc 22 through which it travels and opposite to the next step 19 of the series of steps of the abutment 11. Thus the next coöperation of the same abutment 11 and the part 12 will permit the drum 1 to shift axially an additional step. The extent of each movement of any one of the abutments 11 is determined by means as a single abutment 23 which limits the pivotal movement of the controlling part or member 12. Obviously when the movement of said member 12 has been limited by the stop or abutment 23 further axial movement of the drum 1 is prevented, thus said member 12 is a lever movable between two abutments. The con-

trolling part 12 is preferably pivoted directly at 24 intermediate of its ends to an arm 25 mounted on the inner end of the shaft 5, the outer end of said arm 25 being arranged opposite to the engaging end of the controlling member 12 and forming the stop or abutment 23 for limiting the pivotal movement of the part 12, against the action of its spring 120. It will be readily understood by those skilled in the art that the abutments 11 are independent of each other and any one may assume positions independent of the other abutments so that one or more of said stops may be in position to permit the drum 1 to be moved an axial or lateral shift of one step, while others of said abutments may be in position to permit shifts of the drums equal to two or more single steps. An adjustable stop 26, Fig. 7, may be provided for determining the starting point of the lever 12, and by means of this stop 26, said lever may be adjusted to move sufficiently to shift the abutments 11 one step or a distance equal to two or more single steps during each coöperation. The abutments 11 may be all moved inwardly to their starting positions, by suitable means common to all of said abutments and shown as a split ring 27 movable in the annular guide 28 formed in the rear face of the plate 14, said ring being formed with a cam 29 which engages projections on the abutments as the ring 27 is turned in the guide of the plate 14, such projections being portions 30 of the springs 18. In the operation of the embodiment of my invention best illustrated in Figs. 1 to 4 inclusive; each workman turns the shaft 5 until the space assigned to him on the record strip is opposite to the printing line (this information being conveyed to him in any suitable manner) and he then moves the shaft 5 axially until the controlling member 12 engages the abutment 23 after having encountered the surfaces 20, 21 of the corresponding abutment 11, and forced said abutment one step radially. It is immaterial in my present invention whether the printing is effected by the movement of the shaft 5, or by additional mechanism. Said abutment having shifted one advance outwardly, the controlling part 12 will upon the making of the next record by the same workman be limited by the next shoulder 19 of the series of shoulders of the same abutment 11, so that the next registration of said workman will be at the side of the preceding one. Thus the printing of two records in the same position is avoided.

In Fig. 8 I have shown each of the plurality of abutments as provided with an elongated surface 31 separating the steps or shoulders 32 of the abutment into two series in order that the record sheet may be divided into two longitudinal portions; and

in Fig. 9 the surfaces 33 against which the single member 34 first strikes are shown as beveled, and the single member 34 as provided with a beveled tooth 35 for coöperating with said surfaces. This arrangement of beveled faces is particularly advantageous in that by reason of the engagement of the beveled faces 33, 35 during the coöperation of the abutment and the controlling part, overthrow of the abutment is prevented.

Fig. 10 illustrates one of the plurality of movable abutments 36 carried by the laterally shiftable element 37, and the single abutment 38 and lever 39 carried by the frame 40. Such an arrangement of the abutments is particularly advantageous in that they can be all returned to their starting position by throwing a cam 41 by hand into position to engage said abutments and force the same radially when the hand shaft 42, which carries the drum 37 is rotated.

In Fig. 11 is shown a double shiftable element, or drum 43 which may be shifted laterally in either direction from its starting point, indicated by the arrows 44, into the several positions indicated by arrow 45. The movement of the drum 43 to the left is controlled by one series of movable abutments one of which as 46 is shown, the single 30 abutment 47 and lever 48, and to the right by another series of movable abutments one of which as 49 is shown, and another single abutment 50 and lever 51.

In Fig. 12 is shown a construction in which each movable abutment 52 is shifted radially during the return of the hand shaft 53 carrying the drum not shown instead of by the inward movement of said shaft. This shifting movement is brought about by forming each shoulder 54 of the abutment 52 with a beveled face 55 which coöperates with a beveled face 56 at the end of the lever 57. During the inward movement of the shaft 53, the beveled face 56 of the lever 57 engages but does not act on, one of the beveled faces 55 of the abutment 52, so that during retrograde movement of the hand shaft 53 the beveled faces 55, 56 being engaged, the beveled face 55 will act on the bevel face 56 and force the abutment 52 upwardly, the lever 57 being held from pivotal movement during retrograde movement of the hand shaft by a trigger 58, which engages a knock off device 59 at the end of each retrograde movement of the hand shaft.

What I claim is:—

1. An employees' time recorder embodying a blank carrier and an impression making element, the blank carrier being movable 60 different distances in a given path relative to the impression making element, and means controlled by separate recording operations of the time recorder by an employee for stopping the blank carrier in different positions in said path, which posi-

tions correspond to such operations, substantially as and for the purpose described.

2. In a time recorder, the combination of a rotatable and axially movable drum adapted to support a record sheet, means consisting of an annular series of radially movable abutment plates, each having an inclined series of shoulders on one of its edges, and other means comprising a part facing said series of abutment plates, one of said means being rotatable and movable axially in company with the drum, and a pivoted member carried by said part for coöperating with the shouldered edges of said abutment plates singly to shift the same radially step by step, substantially as and for the purpose specified.

3. In a time recorder, a rotatable and axially movable drum adapted to support a record sheet, a device connected with the drum to revolve and move axially therewith, an annular series of radially movable and axially stationary abutment plates, each having on one of its edges an inclined series of shoulders, and a finger pivoted on the said device for coöperating with the abutment plates singly to shift the same radially step by step, substantially as and for the purpose set forth.

4. In a time recorder, a rotatable and axially movable drum adapted to support a record sheet, an imprint making element a device connected with the drum to revolve and move axially therewith, said device including a rigid member and a pivoted member, and an annular series of radially movable and axially stationary abutment plates, each having on one of its edges an inclined series of shoulders, said movable member coöperating with the shoulders of said abutment plates singly for shifting the same radially step by step, substantially as and for the purpose described.

5. In a locating mechanism and in combination, a shiftable member having operating surfaces disposed at an angle to each other, and a coöperating member movable toward and from the first-named member and having its movement arrested by one of said operating surfaces and coöperating with the other operating surface for shifting said member for carrying the first-named operating surface out of the path traversed by the second member in the succeeding operation thereof, substantially as and for the purpose specified.

6. In a workman's time recorder, a locating mechanism comprising a shiftable member having operating surfaces disposed at an angle to each other, and a coöperating member movable toward and from the first-named member and including a part movable in an arc, one of the operating surfaces of the first member acting as a stop for limiting the movement of the second member, and

said part movable in an arc engaging the other surface of the first member and shifting the latter for carrying the first-named operating surface out of the path traversed by the second member in the succeeding movement thereof toward the first-named part, substantially as and for the purpose set forth.

7. In a workman's time recorder, a locating mechanism comprising a member having a series of operating surfaces with adjacent surfaces disposed at an angle to each other, and a second member movable in a rectilinear direction toward and from the first-named member and including a rigid member and a part movable in an arc, said part movable in an arc being arrested by one of said operating surfaces and in the continued movement of the second-named member acting upon the adjacent disposed operating surfaces for shifting the first-named part in a direction at an angle to said rectilinear direction, and said second-named member being arrested upon the rigid part thereof engaging said part movable in the arc, substantially as and for the purpose described.

8. The combination of a shiftable element, and means for determining successive positions of said element comprising two members, one an abutment having a series of consecutively arranged shoulders, and the other a part for coöperating successively with the shoulders, one of said members being shiftable with the shiftable element into and out of engagement with the other member and said part operating to move one shoulder out of operative position and thereby present the successive shoulder in position to coact with said part during the next co-operation of the members, substantially as and for the purpose set forth.

9. The combination of a shiftable element, and means for determining successive positions of said element comprising two members, one an abutment having a series of consecutively arranged shoulders, and the other a pivoted part for coöperating successively with the shoulders, one of said members being shiftable with the shiftable element into and out of engagement with the other member, and said part being movable on its pivot by the shifting movement of said element while said part is engaged with one of the shoulders, and said part, during its pivotal movement, operating to move one shoulder out of operative position and thereby present the successive shoulder in position to coact with said part during the next coöperation of the members, substantially as and for the purpose described.

10. The combination of a shiftable element, and means for determining successive positions of said element comprising two members, one an abutment having a series of

consecutively arranged shoulders, and the other a part for coöperating with the shoulders, one of said members being shiftable with the shiftable element into and out of engagement with the other member and one of said members being movable a step by the other member during each coöperation of the members in order to position the next shoulder of the abutment and said part for the successive coöperation of said members, substantially as and for the purpose specified.

11. The combination of a shiftable element, and means for determining successive positions of said element comprising two members, one an abutment having a series of consecutively arranged shoulders and the other a part for coöperating with the shoulders, one of said members being shiftable with the shiftable element into and out of engagement with the other member and one of said members being movable a step by the other member during each coöperation of the members in order to position the next shoulder of the abutment and said part for the successive coöperation of said members, and a stop for determining the extent of movement of the movable member, substantially as and for the purpose set forth.

12. The combination of a shiftable element, and means for determining successive positions of said element comprising two members, one of said members being movable with the shiftable element into and out of engagement with the other member, and one of said members being pivoted and the other being movable a predetermined distance by the pivoted member during each coöperation of said members, and a stop for limiting the pivotal movement of the pivoted member after the same has moved the other member a predetermined distance, substantially as and for the purpose described.

13. The combination of a shiftable element, and means for determining successive positions of said element comprising two abutments, one being movable with the shiftable element and the other being shiftable relatively to said element, and a member controlled in its operation by the shifting of said element and coöperating with the abutments for moving the shiftable abutment a predetermined distance during each shifting of said element, substantially as and for the purpose specified.

14. The combination of a shiftable element, and means for determining successive positions of said element comprising two abutments, one being movable with the shiftable element and the other being shiftable relatively to said element, and a pivoted lever controlled in its movement upon its pivot by the shifting movement of said element, the lever having one end arranged between the abutments and operating to en-

gage and move the shiftable abutment a predetermined distance during each shifting of said element and be engaged and limited in its pivotal movement by the other abutment, substantially as and for the purpose set forth.

15. The combination of a fixed element, a movable element shiftable laterally and longitudinally into a plurality of positions, and means for determining successive lateral positions of the shiftable element when in any one of its longitudinal positions, said means including a plurality of members, one only for each of the longitudinal positions assumed by the shiftable element, said members being associated with one of said elements and shiftable independently of each other, and a single member associated with the other element for controlling the shifting of any one of the plurality of members, substantially as and for the purpose described.

20. The combination of a fixed element, a movable element shiftable laterally and longitudinally into a plurality of positions, and means for determining successive lateral positions of the shiftable element when in any one of its longitudinal positions, said means including a plurality of members, one for each of the longitudinal positions assumed by the shiftable element, said members being associated with one of said elements and shiftable independently of each other, and a single pivoted member associated with the other element and operating to shift any one of the plurality of members during the pivotal movement of the pivoted member, substantially as and for the purpose specified.

25. The combination of a fixed element, a movable element shiftable laterally and longitudinally into a plurality of positions, and means for determining successive lateral positions of the shiftable element when in any one of its longitudinal positions, said means including a plurality of abutments one for each of the longitudinal positions assumed by the shiftable element, the abutments being associated with one of said elements and shiftable independently of each other, a relatively fixed abutment associated with the other element, and a controlling part associated with said other element and movable between the abutments for controlling the shifting of any one of the plurality of abutments, substantially as and for the purpose set forth.

30. The combination of a fixed element, a movable element shiftable laterally and longitudinally into a plurality of positions, and means for determining successive lateral positions of the shiftable element when in any one of its longitudinal positions, said means including a plurality of abutments one for each of the longitudinal positions assumed

by the shiftable element, said abutments being associated with one of said elements, and each being provided with a series of consecutively arranged shoulders, and a single movable member associated with the other element and movable into engagement with one of the shoulders of the corresponding abutment during the lateral movement of the shiftable element and operating to move one shoulder of the corresponding abutment a predetermined distance and thereby present a successive shoulder into position to coat therewith during the next coöperation of the members, substantially as and for the purpose described.

35. The combination of a shiftable element, and means for determining successive positions of said element comprising two members, one of said members being movable with the shiftable element into and out of engagement with the other member, and one of said members being movable a predetermined distance by the other member, during each coöperation of said members, in a direction at an angle to the direction of the shifting movement of said element, in order to relatively position said members for the next coöperation thereof, substantially as and for the purpose described.

40. The combination of a shiftable element, and means for determining successive positions of said element comprising two members, one of said members being movable with the shiftable element into and out of engagement with the other member, and one of said members being pivoted and the other being movable a predetermined distance by the pivotal movement of the pivoted member, during each coöperation of said members, in a direction at an angle to the direction of the shifting movement of said element, in order to relatively position said members for the next coöperation thereof, substantially as and for the purpose specified.

45. The combination of a shiftable element, and means for determining successive positions of said element comprising two members, one a controlling part and the other an abutment, one of said members being movable with the shiftable element into and out of engagement with the other member, and the abutment being movable a predetermined distance by said part, during each coöperation thereof, in a direction at an angle to the direction of the shifting movement of said element, in order to relatively position said members for the next coöperation thereof, substantially as and for the purpose set forth.

50. The combination of a shiftable element, and means for determining successive positions of said element comprising two members, one a controlling part and the other an abutment, the controlling part be-

ing pivotally connected to the shiftable element, and movable into and out of engagement with the abutment, and the abutment being movable a predetermined distance by 5 said part in a direction at an angle to the direction of the shifting movement of said element, the controlling part moving on its pivot, after first engaging the abutment, and during its pivotal movement, moving the 10 abutment a predetermined distance, in order to position said abutment for the next co-operation with the controlling part, substantially as and for the purpose described.

23. The combination of a shiftable element, and means for determining successive 15 positions of said element comprising two members, one an abutment having a series of shoulders arranged in steps, and the other a part for coöperating with said shoulders, one 20 of said members being movable with the shiftable element into and out of engagement with the other member, and one of said members being movable step by step by the other member in a direction at an angle to 25 the direction of the shifting movement of said element, in order to position the next shoulder of the abutment and said part, for the successive coöperation of said members, substantially as and for the purpose specified. 30

24. The combination of a shiftable element, and means for determining successive 35 positions of said element comprising two members, one of said members being movable 40 with the shiftable element at will into and out of engagement with the other member, and one of said members being movable a predetermined distance by the other member, during each coöperation of said members, in a direction at an angle to the direction 45 of the shifting movement of said element, in order to relatively position said members for the next coöperation thereof, and a stop for determining the extent of movement of the movable member by the other member, substantially as and for the purpose set forth.

25. The combination of a shiftable element, and means for determining successive 50 positions of said element comprising two members, one of said members being movable with the shiftable element at will into and out of engagement with the other member, and one of said members being pivoted 55 and the other being movable a predetermined distance by the pivoted member, during each coöperation of said members, in a direction at an angle to the direction of the shifting movement of said element, and a 60 stop for limiting the pivotal movement of the pivoted member, after the same has moved the other member the predetermined distance, substantially as and for the purpose described.

26. The combination of a shiftable ele-

ment, and means for determining successive 70 positions of said element comprising two members, one a controlling part and the other an abutment, said part being pivotally connected to the shiftable element and movable into and out of engagement with the abutment, and the abutment being movable a predetermined distance by said part in a direction at an angle to the direction of the shifting movement of said element, the 75 controlling part moving on its pivot, after first engaging the abutment, and during its pivotal movement, moving the abutment the predetermined distance, in order to position 80 said abutment for the next coöperation with the controlling part, and a stop for determining the movement of the abutment, substantially as and for the purpose specified.

27. The combination of a shiftable element, and means for determining successive 85 positions of said element, comprising two members, one a controlling part and the other an abutment, the controlling part being pivotally connected to the shiftable element and movable into and out of engagement with the abutment, and the abutment being movable a predetermined distance by said part, in a direction at an angle to the direction of the shifting movement of said 90 element, the controlling part moving on its pivot, after first engaging the abutment, and during its pivotal movement moving the abutment a predetermined distance, in order to position 95 said abutment for the next coöperation with the controlling part, and a stop for limiting the pivotal movement of said part, substantially as and for the purpose set forth.

28. The combination of a shiftable element, and means for determining successive 100 positions of said element comprising two members, one a controlling part and the other an abutment, the controlling part being pivotally connected to the shiftable element and movable into and out of engagement with the abutment, and the abutment being movable a predetermined distance by said part in a direction at an angle to the direction of shifting movement of said element, the controlling part moving on its pivot, after first engaging the abutment, and during its pivotal movement, moving the abutment a predetermined distance, in order to position 105 said abutment for the next coöperation with the controlling part, and a stop for determining the movement of the abutment, said stop engaging the pivotal part and limiting the pivotal movement 110 thereof, substantially as and for the purpose 115 described.

29. The combination of a shiftable element, and means for determining successive 120 positions of said element comprising two members, one a controlling part and the 125 described.

other an abutment having a series of shoulders arranged in steps, the controlling part being pivotally connected to the shiftable element and movable therewith into and out of successive engagement with said shoulders, and the abutment being movable step by step by the pivoted member in a direction at an angle to the direction of shifting movement of said element as said controlling part moves on its pivot, and a stop for limiting pivotal movement of the controlling part, substantially as and for the purpose specified.

30. The combination of a shiftable element, and means for determining successive positions of said elements comprising two members, one a controlling part and the other an abutment having a series of shoulders arranged in steps, each shoulder having surfaces arranged at an angle to each other, and the said controlling part being pivotally connected to the shiftable element and movable therewith into engagement with said shoulders of the abutment, said part engaging one surface of the shoulder with which said part is arranged to coact for limiting further movement of the pivoted part with the shiftable element, and being movable on its pivot during further movement of the shiftable element and engaging the other surface of said shoulder for forcing the abutment one step in a direction at an angle to the direction of shifting movement of said element, in order to relatively position 35 the next shoulder of the abutment and said controlling part for the successive coöperation of said members, and a stop for limiting the pivotal movement to the controlling part, substantially as and for the purpose 40 set forth.

31. The combination of a shiftable element, and means for determining successive positions of said element comprising two members, one an abutment movable step by 45 step in a direction at an angle to the direction of the shifting movement of said element, and having a series of shoulders arranged in steps, each shoulder having surfaces arranged at an angle to each other, 50 and the other a controlling part for coöperating successively with the shoulders of the abutment, one of said members being movable with the shiftable element into and out of engagement with the other member, 55 and the controlling part being pivoted intermediate of its ends and one end thereof coacting first with one of the faces of the shoulder arranged to coact with said part, in order to effect the pivotal movement of 60 the controlling part, and then engaging the other face of said shoulder during the pivotal movement of the controlling part, and moving the abutment one step, a spring acting in the other end of said part, and an 65 abutment for limiting the pivotal movement

of the controlling part, substantially as and for the purpose described.

32. The combination of a shiftable element, and means for determining successive positions of said element comprising two abutments, one being movable with the shiftable element and the other being fixed from shifting movement therewith, and being movable in a direction at an angle to the shifting movement of said element, and a 75 member controlled in its operation by the shifting of said element and coöperating with the abutments for moving the movable abutment a predetermined distance during each shifting of said element, substantially 80 as and for the purpose specified.

33. The combination of a shiftable element, and means for determining successive positions of said element comprising two abutments, one being movable with the shiftable element, and the other being fixed from shifting movement therewith, and being movable in a direction at an angle to the shifting movement of said element, and a pivoted lever controlled in its movement 85 upon its pivot by the shifting movement of said element, the lever having one end arranged between the abutments, and operating to engage and move the movable abutment a predetermined distance during each 90 shifting of said element, and to engage and be limited in its pivotal movement by the other abutment, substantially as and for the purpose set forth.

34. The combination of a shiftable element, and means for determining successive positions of said element comprising two abutments, one being movable with the shiftable element and the other being fixed from shifting movement therewith, and being 100 movable in a direction at an angle to the shifting movement of said element, and a lever pivoted to the abutment movable with the shiftable element, and interposed between the abutments, the lever operating to 105 engage the movable abutment as the shiftable element approaches the end of its shifting movement, and to move on its pivot and thereby shift the movable abutment until the pivotal movement of said lever is limited by engagement with the other abutment, substantially as and for the purpose 110 described.

35. The combination of a shiftable element, and means for determining successive positions of said element comprising two abutments, one being movable with the shiftable element, and the other being fixed from shifting movement therewith, and one being 115 movable in a direction at an angle to the shifting movement of said element, the latter abutment being also formed with a series of shoulders arranged in steps, each step or shoulder having engaging surfaces arranged at an angle to each other, and a member con- 120

125

- trolled in its operation by the shifting of said element and coöperating with said abutments, said member engaging one surface of the shoulder with which said member is arranged to coact for limiting further movement of said member with the shiftable element, and being moved relatively to said element into engagement with the other surface of said shoulder for shifting the movable abutment until said member is limited by the other abutment, substantially as and for the purpose specified.
36. The combination of a shiftable element, and means for determining successive positions of said element comprising two abutments, one being movable with the shiftable element and the other being fixed from shifting movement therewith, and being movable in a direction at an angle to the shifting movement of said element, the latter abutment being also formed with a series of shoulders arranged in steps, each step or shoulder having engaging surfaces arranged at an angle to each other, and a lever pivoted to the abutment movable with the shiftable element and having one end arranged between the abutments, said lever operating to engage one surface of the shoulder with which it is arranged to coact and to be thereby moved on its pivot relatively to the abutment to which it is pivoted until limited from further pivotal movement by the last mentioned abutment, the lever engaging the other surface of said shoulder during its pivotal movement, and moving the movable abutment a predetermined distance during such pivotal movement, substantially as and for the purpose set forth.
37. The combination of a fixed element, a movable element shiftable laterally and longitudinally into a plurality of positions, and means for determining successive lateral positions of the shiftable element when in any one of its longitudinal positions, said means including a plurality of members, one for each of the longitudinal positions assumed by the shiftable element, said members being associated with one of said elements and being shiftable independently of each other in a direction at an angle to the lateral movement of the shiftable element, and a single member associated with the other element for controlling the shifting of any one of the plurality of members, substantially as and for the purpose described.
38. The combination of a fixed supporting element, a movable element shiftable laterally and longitudinally into a plurality of positions, and means for determining successive lateral positions of the shiftable element when in any one of its longitudinal positions, said means including a plurality of members, one for each of the longitudinal positions assumed by the shiftable element,

- said members being associated with one of said elements and being shiftable independently of each other in a direction at an angle to the lateral movement of the shiftable element, and a pivoted member associated with the other element for controlling the shifting of any one of the plurality of members, substantially as and for the purpose specified.
39. The combination of a fixed element, a movable element shiftable laterally and longitudinally into a plurality of positions, and means for determining successive lateral positions of the shiftable element when in any one of its longitudinal positions, said means including a plurality of members, one for each of the longitudinal positions assumed by the shiftable element, said members being associated with one of said elements and being shiftable independently of each other in a direction at an angle to the lateral movement of the shiftable element, a single member associated with the other element for controlling the shifting of any one of the plurality of members, and a stop for determining the extent of each shifting movement of each of the plurality of members, substantially as and for the purpose set forth.
40. The combination of a fixed supporting element, a movable element shiftable laterally and longitudinally into a plurality of positions, and means for determining successive lateral positions of the shiftable element when in any one of its longitudinal positions, said means including a plurality of members, one for each of the longitudinal positions assumed by the shiftable element, said members being associated with one of said elements and being shiftable independently of each other in a direction at an angle to the lateral movement of the shiftable element, a pivoted member associated with the other element for controlling the shifting movement of any one of the plurality of members, and a stop for limiting the pivotal movement of the pivoted member when the same has shifted any one of the plurality of members, substantially as and for the purpose described.
41. The combination of a fixed supporting element, a movable element shiftable laterally and longitudinally into a plurality of positions, and means for determining successive lateral positions of the shiftable element when in any one of its longitudinal positions, said means including a plurality of members, one for each of the longitudinal positions assumed by the shiftable element, said members being associated with one of said elements and being shiftable independently of each other in a direction at an angle to the lateral movement of the shiftable element and each having a series of shoulders arranged in steps, and a piv-

oted member associated with the other element for coacting with any one of the shoulders of any one of the plurality of members and controlling the shifting of said 5 member, and arranging another shoulder of the same one of the plurality of members in position for the next coöperation thereof with the pivoted member, and a stop for limiting the pivotal movement of the 10 pivoted member, substantially as and for the purpose specified.

42. The combination of a fixed supporting element and a movable element shiftable laterally and longitudinally into a plurality 15 of positions, and means for determining successive lateral positions of the shiftable element when in any one of its longitudinal positions, said means including a plurality of abutments, one for each of the longitudinal 20 positions assumed by the shiftable element, said abutments being associated with one of said elements, and being movable independently of each other in a direction at an angle to the lateral movement of the 25 shiftable element, a single abutment associated with the other element for coöperating with any one of the plurality of abutments and limiting the lateral movement of the shiftable element, and a member controlled 30 in its operation by the lateral shifting of the shiftable element and coöperating with the abutments, said member extending between the single abutment and the plurality of abutments, and operating to 35 engage a predetermined one of the plurality of abutments during each coöperation of the abutments and to thereby move said predetermined abutment until the movement of said member is limited by the single 40 abutment, substantially as and for the purpose set forth.

43. The combination of a fixed supporting element and a movable element shiftable laterally and longitudinally into a plurality 45 of positions, and means for determining successive lateral positions of the shiftable element when in any one of its longitudinal positions, said means including a plurality of abutments, one for each of the longitudinal 50 positions assumed by the shiftable element, said abutments being associated with one of said elements, and being movable independently of each other in a direction at an angle to the lateral movement of the 55 shiftable element, a single abutment associated with the other element for coöperating with any one of the plurality of abutments, and limiting the lateral movement of the shiftable element, and a lever pivoted 60 to the single abutment and operating to engage a predetermined one of the plurality of abutments as the shiftable element approaches the end of the shifting movement and to be moved on its pivot and thereby move the said predetermined abutment un-

til the pivotal movement of the lever is limited by the single abutment, substantially as and for the purpose described.

44. The combination of a fixed element, and a movable element shiftable laterally, 70 and longitudinally into a plurality of positions, and means for determining successive lateral positions of said elements in one of its longitudinal positions, said means including a plurality of abutments one for 75 each of the longitudinal positions of the shiftable element, said abutments being carried by the fixed element and being movable independently of each other in a direction at an angle to the lateral movement 80 of the shiftable element, a single abutment movable with the shiftable element, and a lever pivoted to the single abutment, and extending between the single and the plurality of abutments, the movement of the 85 shiftable element longitudinally arranging the single abutment and lever, and a predetermined one of the plurality of members in position to coöperate when the movable element is shifting laterally and the lever 90 operating to engage the predetermined one of the plurality of abutments as the shiftable element approaches the end of the shifting movement and to move on its pivot and thereby move said predetermined abutment the lever is engaged by the single 95 abutment, substantially as and for the purpose specified.

45. The combination of a fixed element, a rotatable and axially-shiftable element, and 100 means for determining successive lateral or axial positions of the latter element when in any one of its positions assumed when moved about its axis, said means including a plurality of members one for each of the 105 positions assumed by the rotatable element when moved about its axis, said members being associated with one of said elements and being movable independently of each other radially relatively to the axis of the 110 rotatable element, and a single member associated with the other element, substantially as and for the purpose set forth.

46. The combination of a fixed supporting element, a rotatable and axially-shiftable element, and means for determining successive axial positions of the rotatable element when in any one of its positions assumed when moved about its axis, said 115 means including a plurality of members, one for each of the positions assumed by the rotatable element when moved about its axis, said members being movable independently of each other in a direction radially relatively to the axis of the rotatable element and a pivoted member associated with the other element, substantially as and for the purpose described.

47. The combination of a fixed supporting element, a rotatable and axially-shiftable 120

- element, and means for determining successive axial positions of the rotatable element when in any one of its positions assumed when moved about its axis, said means including a plurality of members, one for each of the positions assumed by the rotatable element when moved about its axis, said members being movable independently of each other in a direction radially relatively to the axis of the rotatable element, a pivoted member associated with the other element, and a stop for limiting the pivotal movement of the pivoted member when the same has shifted the predetermined member, substantially as and for the purpose specified.
48. The combination of a fixed supporting element, a rotatable element shiftable axially into a plurality of positions, and means for determining successive axial positions of the rotatable element when in any one of its positions assumed when moved about its axis, said means including a plurality of abutments one for each of the positions assumed by the rotatable element when moved about its axis, said abutments being associated with one of said elements and being movable independently of each other radially relatively to the axis of the rotatable element, a single abutment associated with the other element for coöperating with any one of the plurality of abutments and limiting the axial movement of the rotatable element, and a member controlled in its operation by the axial shifting of the rotatable element, said member extending between the plurality of abutments and the single abutment and operating to engage a predetermined one of the plurality of abutments during each coöperation of said predetermined abutment and the single abutment, and to be thereby moved until limited by the single abutment, said member during its movement serving to shift the movable abutment with which it is coöperating, in the radial direction in order to position said one of the plurality of abutments and the single abutment for the next coöperation thereof, substantially as and for the purpose set forth.
49. The combination of a fixed element, a rotatable element shiftable axially into a plurality of positions, and means for determining successive lateral positions of the rotatable element when in any one of its positions assumed when rotating about its axis, said means including a plurality of abutments one for each of the positions assumed by the rotatable element when moved about its axis, said abutments being associated with one of said elements and being movable independently of each other radially relatively to the axis of said element, a single abutment associated with the other element for coöperating with any one of the plurality of abutments and limiting the axial movement of the rotatable element, a lever piv-

oted to the single abutment, the lever operating to engage a predetermined one of the abutments as the shiftable element approaches the end of its axial movement and to be moved on its pivot and thereby move the predetermined abutment radially until the pivotal movement of said lever is limited by the single abutment, substantially as and for the purpose described.

50. The combination of a fixed element, a movable element shiftable laterally and longitudinally into a plurality of positions, means for determining successive lateral positions of the shiftable element when in any one of its longitudinal positions, said means including a plurality of members, one for each of the longitudinal positions assumed by the shiftable element, said members being associated with one of said elements and being shiftable independently of each other in a direction at an angle to the lateral movement of the shiftable element, and manual means for returning the plurality of members to their initial positions, substantially as and for the purpose specified.

51. The combination of a fixed supporting element, a movable element shiftable laterally and longitudinally into a plurality of positions, means for determining successive lateral positions of the shiftable element when in any one of its longitudinal positions, said means including a plurality of members, one for each of the longitudinal positions of the shiftable element, said members being associated with one of said elements and being movable independently of each other in a direction at an angle to the lateral movement of the shiftable element, a single member associated with the other element for controlling the shifting of any one of the plurality of members, and manual means common to all of the plurality of members for returning said members to their initial positions, substantially as and for the purpose set forth.

52. The combination of a main frame, frame elements supported by the main frame and arranged parallel to each other, said frame elements being formed with a series of guides in their opposing faces, a movable element shiftable laterally and longitudinally in a direction parallel to the frame elements into a plurality of positions, and means for determining successive lateral positions of the shiftable element when in any one of its longitudinal positions, said means including a plurality of members movable in said guides independently of each other, and a single member associated with the shiftable element for controlling the shifting of any one of the plurality of members in its guides, substantially as and for the purpose described.

53. The combination of a main frame, a hollow shaft journaled in the main frame,

two frame elements extending around the axis of the shaft and arranged parallel to each other, said frame elements being formed with grooves in their opposing faces, 5 the grooves being arranged radially with the axis of the shaft, a drum rotatably mounted on the hollow shaft and shiftable axially theron, an operating shaft extending through the hollow shaft and connected 10 to the drum for rotating and shifting axially said drum, an arm mounted on the inner end of the shaft and provided with a single abutment at its outer end and a lever pivoted intermediate of its ends to said arm, 15 an end of the lever being movable beyond the end of the single abutment, and a plurality of abutments movable in the grooves of the elements, rotation of the drum by the hand-shaft serving to carry said arm and lever opposite to any one of the abutments, substantially as and for the purpose specified.

54. The combination of a main frame, frame elements supported by the main 25 frame and arranged parallel to each other, said frame elements being formed with a series of guides in their opposing faces, a movable element shiftable laterally and longitudinally in a direction parallel to the 30 frame elements into a plurality of positions, means for determining successive lateral positions of the shiftable element when in any one of its longitudinal positions, said means including a plurality of members 35 movable in said guides independently of each other, and a single member associated with the shiftable element for controlling the shifting of any one of the plurality of members in its guides, and means common 40 to all of the plurality of members for returning the same to their initial positions, substantially as and for the purpose set forth.

55. The combination of a main frame, a 45 hollow shaft journaled in the main frame, frame elements extending around the axis of the shaft and arranged parallel to each other, said frame elements being formed with guides in their opposing faces, the 50 guides being arranged radially with the axis of the shaft, a drum rotatably mounted on the hollow shaft and shiftable axially theron, means associated with the drum for rotating and shifting axially said drum, a 55 plurality of abutments movable in the guides of the frame elements, a single element rotatable with the drum for controlling the shifting of any one of the plurality of members in its guides and movable means 60 supported by one of the frame elements for engaging the plurality of elements and returning the same to their initial positions, substantially as and for the purpose described.

65 56. The combination of a fixed element a

movable element shiftable laterally and longitudinally into a plurality of positions, and means for determining successive lateral positions of the shiftable element when in any one of its longitudinal positions, said 70 means including a plurality of members one for each of the longitudinal positions assumed by the shiftable element, said members being associated with one of said elements and being shiftable independently of each other in a direction at an angle to the lateral movement of the shiftable element, and frictional devices for holding said members in the positions to which they are shifted, substantially as and for the purpose 75 specified. 80

57. The combination of a fixed element, a movable element shiftable laterally and longitudinally into a plurality of positions, and means for determining successive lateral positions of the shiftable element when in any one of its longitudinal positions, said means including a plurality of members, one for each of the longitudinal positions assumed by the shiftable element, 85 said members being associated with one of said elements and being shiftable independently of each other in a direction at an angle to the lateral movement of the shiftable element, and a spring associated with each of said members and frictionally engaging the element supporting said plurality of members, substantially as and for the purpose set forth. 90

58. The combination of a main frame, two frame elements arranged parallel to each other and formed with guides in their opposing faces, one of said frame elements being formed with slots extending through opposite faces thereof, a movable element 100 shiftable laterally and longitudinally in a direction parallel to said frame elements, and means for determining successive lateral positions of the shiftable element when in any one of its longitudinal positions, said 105 means including a plurality of members movable in said guides and having devices connected thereto and extending through the slots for slidably engaging the outer face of the frame element in which said slots are formed, and frictionally holding said members in the positions to which they are moved, substantially as and for the purpose described. 110

59. In a workman's time-recorder, a printing couple including a type carrying element, and an element for supporting a record-sheet having spaces for the records of a plurality of workmen, a single member individual to each record space for determining 120 the point at which the printing takes place and thereby preventing the printing of a record twice at the same point, and means for shifting the single member a predetermined amount during each operation of the 125 130

printing couple, substantially as and for the purpose described.

60. In a workman's time-recorder, a printing couple including a type carrying element, and an element for supporting a record-sheet having spaces for the records of a plurality of workmen, a single member individual to each space, a single member common to all of the record spaces for co-operating with the first-mentioned member and determining the point at which the printing takes place and preventing the printing of records twice at the same point, and means for shifting the corresponding individual member a predetermined amount during each operation of the printing couple, substantially as and for the purpose specified.

61. In a workman's time-recorder, a printing couple including a type carrying element, and an element for supporting a record-sheet having spaces for the records of a plurality of workmen, a single shiftable member individual to each record space and having a plurality of consecutively arranged shoulders, a single member common to all of the record spaces for co-operating with the first-mentioned member for determining the point at which the printing takes place and preventing the printing of records twice at the same point, the common member being pivoted and coacting successively with the shoulders of any one of the shiftable members and operating during its pivotal movement to shift the shoulder with which said pivoted member is coacting out of operative position and present another shoulder in the path of said pivoted member, substantially as and for the purpose specified.

62. In a recorder for a plurality of men, and in combination, an impression making element, an element carrying an impression receiving part having a space individual to each man, and means including a manual for shifting the second element relatively to the first to bring any one of said spaces into registration with the first element and for shifting the second element relatively to the first variable distances from an initial starting point during successive actuations of said manual by any one of said plurality of men.

63. In a recorder for printing records of a plurality of men in columns individual to such men, and with the successive records of the individual men separated by substantially equidistant spaces, an impression making element, an element carrying an impression receiving surface, the last-named element having movement in one direction for registering any selected column with the impression making element, and having movement in a second direction for effecting said spacing between successive records,

a manual operatively connected for effecting said movement of the second element, and a mechanism for controlling the extent of said second movement.

64. In a recorder for printing records of a plurality of men in columns individual to such men, and with the successive records of the individual men separated by substantially equidistant spaces, an impression making element, an element carrying an impression receiving surface, the last-named element having movement in one direction for registering any selected column with the impression making element, and having movement in a second direction for effecting said spacing between successive records, a manual operatively connected for effecting said movement of the second element, and a mechanism for controlling the extent of said second movement including means individual to each man.

65. In a recorder for printing records of a plurality of men in columns individual to such men, and with the successive records of the individual men separated by substantially equidistant spaces, an impression making element, an element carrying an impression receiving surface, the last-named element having movement in one direction for registering any selected column with the impression making element, and having movement in a second direction for effecting said spacing between successive records, a manual operatively connected for effecting said movement of the second element, and a mechanism for controlling the extent of said second movement including means individual to each man, and a device common to all of the men having independent co-operation with each of said individual means.

66. In a recorder for a plurality of workmen, an impression making element, a second element for holding an impression receiving surface, a manual operatively connected for moving the second element in one direction or path, and means for so controlling the extent of said movement that under successive actuations of said manual by the same workman, the range of said movement of the second element will be increased, said means including two co-operating mechanisms, one common to all of the workmen, and the other individual to each workman.

67. In a recorder for printing records of a plurality of men in columns individual to such men and with the successive records of the individual men separated by substantially equidistant spaces, an impression making element, and an element carrying an impression receiving surface, said elements having relative movement in one direction for registering any selected column with the impression making element and having movement in a second direction for effecting

5 said spacing between successive records, a manual operatively connected for effecting said movements of said elements and a mechanism for controlling the extent of said second movement including a shiftable member individual to each man and provided with a plurality of stop shoulders.

68. In a recorder for printing records of a plurality of men in columns individual to 10 such men and with the successive records of the individual men separated by substantially equidistant spaces, an impression making element, and an element carrying an impression receiving surface, said elements 15 having relative movement in one direction for registering any selected column with the impression making element and having movement in a second direction for effecting said spacing between successive records, a 20 manual operatively connected for effecting said movements of said elements and a mechanism for controlling the extent of said second movement, including a shiftable member individual to each man and provided 25 with a plurality of stop shoulders, and a device common to all of the men and independently coacting with each of said shiftable members.

69. In a recorder for a plurality of men, 30 and in combination, an impression making element, an element carrying an impression receiving part having a column individual to each man, means for shifting one of said elements relatively to the other to bring any 35 one of said columns into registration with the impression making element, and for effecting relative shifting movement of said elements for spacing between successive registrations in each column, and means for 40 controlling the last-named movement including a notched abutment individual to each of the columns of the impression receiving part.

70. In a recorder for a plurality of men, 45 and in combination, an impression making element, an element carrying an impression receiving part having a column individual to each man, means for shifting one of said elements relatively to the other to bring any 50 one of said columns into registration with the impression making element, and for effecting relative shifting movement of said elements for spacing between successive registrations in each column, and means for 55 controlling the last-named movement including a notched abutment associated with each of the columns of the impression receiving part, and means for independently shifting said abutments.

60 71. In a recorder for recording records of a plurality of men, and in combination, an impression making element, an element carrying an impression receiving part having a column individual to each man, means for 65 shifting one of said elements relatively to

the other to bring any one of said columns into registration with the impression making element, and for effecting relative shifting movement of said elements for spacing between successive registrations in each 70 column, and means for controlling the last-named movement including a notched abutment associated with each of the columns of the impression receiving part, and a single part common to all of the abutments for 75 shifting the latter individually and independently of one another.

72. In a recorder for recording records of a plurality of men, and in combination, an impression making element, an element carrying an impression receiving part having a column individual to each man, means for shifting one of said elements relatively to the other to bring any one of said columns into registration with the impression making element, and for effecting relative shifting movement of said elements for spacing between successive registrations in each 80 column, and means for controlling the last-named movement including a notched abutment associated with each of the columns of the impression receiving part, and a single part common to all of the abutments for 85 shifting the latter individually and independently of one another, said single part 90 being carried by, and movable with the means for effecting the last-named relative movement.

73. A recorder for recording records for a plurality of men including an impression 100 making element, an element carrying an impression receiving part having spaces individual to the aforesaid men, a manual, and operating mechanism associated therewith, said second element having relative movement from an initial starting position in a direction lengthwise of said spaces upon the operation of said manual in one direction, and means for controlling the last-named movement comprising a part individual to 105 each space and having a series of separated stop surfaces.

74. A recorder for a plurality of men including an impression making element, an element carrying an impression receiving 110 part having spaces individual to the aforesaid men; a manual, and operating mechanism associated therewith, said second element having relative movement from an initial starting position in a direction 115 lengthwise of said spaces upon the operation of said manual in one direction, and means for determining the extent of such movement comprising a device common to all of the spaces, and coacting means individual 120 to each space, and operating to control the position of said element with respect only to the space with which said coacting means is associated.

75. In a recorder, an impression making 130

element, a second element for holding an impression receiving surface, a manual operatively connected for effecting a relative movement of said elements in one direction, or path, and means for controlling the extent of said movement so that under successive actuations of said manual, the range of said relative movement will be increased.

76. In a recorder, an impression making element, a second element for holding an impression receiving surface, a manual operatively connected for effecting a relative movement of said elements in one direction, or path from an initial starting point, and means for controlling the extent of said movement so that under successive actuations of said manual by the same workman the range of said relative movement will be increased, said means including a shiftable bar having a plurality of operative surfaces.

77. In a recorder, an impression making element, a second element for holding an impression receiving surface, a manual operatively connected for effecting a relative movement of said elements in one direction, or path, and means for so controlling the

extent of said movement that under successive actuations of said manual by the same workman, the range of said relative movement will be increased, said means including a part movable with one of said elements and a coacting member having a plurality of stop surfaces.

78. In a time-recorder for a plurality of workmen, an impression making element, a drum carrying an impression receiving surface having spaces individual to the several workmen, a manual, and means actuated when the manual is operated in one direction for shifting the drum from its position of rest, the extent of said shifting movement being automatically controlled by mechanism individual to each workman.

In testimony whereof, I have hereunto signed my name in the presence of two attesting witnesses at Syracuse, in the county of Onondaga, in the State of New York, this 25 day of August, 1908.

CHARLES E. TOMLINSON.
